AIRCRAFT OR THE LIKE

Edmond R. Doak, Los Angeles, Calif., assignor to Doak Aircraft Co., Inc., Torrance, Calif., a corporation of California

Filed May 25, 1959, Ser. No. 56,056

Term of patent 14 years

(Cl. D71—1)

Fig. 1.

Fig. 2.

Fig. 3.

Fig. 1 is a front elevational view of an aircraft showing my new design;

Fig. 2 is a side elevational view thereof with one of the rotor elements omitted to better illustrate configurational details of the wing; and

Fig. 3 is a plan view taken from the top thereof.

The undisclosed side of the aircraft is a mirror image of the side shown and the bottom thereof is plain.

I claim:

The ornamental design for an aircraft or the like, as shown and described.
